(57) **CLAIM**

The ornamental design for a cuff bracelet as shown and described.

DESCRIPTION

FIG. 1 is a front, top and left side perspective view of a cuff bracelet, showing my new design in a closed position,

FIG. 2 is a right side view thereof;

FIG. 3 is a front view thereof;

FIG. 4 is a left side view thereof;

FIG. 5 is a rear view thereof;

FIG. 6 is a top view thereof;

FIG. 7 is a bottom view thereof; and,

FIG. 8 is a front, top and right side perspective view of the cuff bracelet in an open position.

The broken lines indicate surface ornamentation that forms no part of the claimed design.

1 Claim, 8 Drawing Sheets(56)
